REFRIGERATOR TRAYS

Robert E. Fields, Evansville, Ind., assignor, by mesne assignments, to Whirlpool-Sceger Corporation, a corporation of Delaware

Application September 8, 1953, Serial No. 379,900

1 Claim. (Cl. 312—270)

This invention relates generally to a refrigerator construction, and more particularly to an improved construction for slidably supporting and covering refrigerator pans within a refrigerator cabinet, and further, to an improved method or process for manufacturing such a construction.

As is well known in the art, household refrigerators are generally provided with one or more pans for the storage therein of food, such as fresh fruits or vegetables. These refrigerator pans are usually called crispers. These crispers must be easily removable and replaceable within a refrigerator cabinet and further, some cover means must be provided to prevent undesirable drying out of the fresh fruits and vegetables.

Therefore, it is an object of the present invention to provide improved structure for a refrigerator crisper fulfilling all of the requirements noted above.

It is a further object of the present invention to provide an improved method or process for manufacturing a structure which will fulfill all of the requirements noted above.

A feature of the present invention is the novel molding of a plastic frame with metal inserts therein.

Further objects and features of the present invention will be apparent upon a perusal of the following specification and drawing of which:

Figure 1 is a plan view of a portion of the present invention showing the initial molding thereof;

Figure 2 is a top plan view of the molded elements shown in Figure 1, properly assembled and cooperating with a cover element;

Figure 3 is a partial enlarged cross-sectional view of the structure shown in Figure 2 and taken along the lines 3—3;

Figure 4 is a partial enlarged cross-sectional view of the structure shown in Figure 2 and taken along the line 4—4; and

Figure 5 is a partial elevational view of a portion of a refrigerator cabinet embodying the present invention.

The present embodiment is the preferred embodiment, but it is to be understood that changes can be made in the present embodiment by one skilled in the art without departing from the spirit and scope of this invention.

For a detailed description of the present invention, reference is made to the drawing. Initially, a frame member shown generally with the character 6 is formed. The frame 6 comprises four sides or side members, 10, 11, 12 and 13. Side 10 is formed to have a substantially U-shaped cross-section, as can be seen in Figure 4. Sides 11, 12 and 13 are formed to comprise two conterminous U-shaped channels substantially as shown in cross-section in Figure 3. These sides 10, 11, 12 and 13 are formed of any plastic material well known in the art which is readily moldable and which when molded will have a good structural strength. Sides 10 and 11 are interconnected by a metal insert 14 molded as an integral part therebetween. Sides 11 and 12 are interconnected by a metal insert 15 which is molded as an integral part therebetween. Sides 12 and 13 are interconnected by a

2

metal insert 16 which is molded as an integral part therebetween. The metal inserts 14, 15 and 16 are formed of any material, such as steel, which may be readily flexed, and which will give good structural strength to the above-described connections between the various sides.

To mold the frame 6, a single die (not shown) is used. The die is formed to have four longitudinally spaced molding sections. Adjacent molding sections are interconnected by passageways. The metal inserts 14, 15 and 16 are each positioned within one of the passageways within the die, and the die is then filled with the plastic material required, and the molding operation is then effected. When the frame is then removed from the die, it will have an appearance substantially as shown in Figure 1. Specifically, the four sides 10, 11, 12 and 13 will be formed having the cross-sections described above, having mitered corners as can readily be seen in Figures 1 and 2 and further, being interconnected as a unitary assembly by the three metal inserts 14, 15 and 16.

To assemble the frame 6, the various sides are bent through an angle of 90° until the mitered corners cooperate to form a substantially rectangularly shaped frame 6, as seen in Figure 2. The metal inserts will each be bent through an angle of 90°. End 10a of the side 10 and end 13a of the side 13 will then cooperate to form the fourth corner. Before the ends 10a and 13a are joined together, a rectangular sheet of material 20, such as glass, is positioned within the channel formed in the side 10 and the upper channel formed in each of the sides 11, 12 and 13. The ends 10a and 13a may then be joined together by any connecting means 17 well known in the art. The connecting means 17 may comprise a small bracket, such as shown in Figure 2, fixedly connected between the ends 10a and 13a or, the mounting means may comprise two walls of a refrigerator cabinet. Further, connecting means 17 may take the form of a lock, such that when the frame is mounted within a refrigerator cabinet, the lock may be opened, and the side 10 or 13 may be pivoted away from the remainder of the frame to permit easy removal of the glass panel 20. Also, the glass 20 may be press fitted or cemented into the above noted channels.

After the frame 6 has been assembled, as described above, the frame is mounted within a refrigerator cabinet, such as refrigerator cabinet 21 shown in Figure 5. Refrigerator cabinet 21 is provided with an inner liner 22, as is well known in the art. The frame 6 is positioned within the inner liner 22 and sides 12 and 13 thereof are secured to two of the walls of the inner liner 22. Side 11 is secured to any mounting means 23, well known in the art, for maintaining the frame 6 in proper horizontal alignment. The sides 10 and 12 can then be designated the front portion 10 and the rear portion 12, respectively.

It is intended that the structure of the present invention be used in cooperation with a refrigerator pan, such as refrigerator pan 24 shown in Figure 5. The refrigerator pan 24 is rectangularly shaped and has a length and width substantially equal to the length and width of the frame 6. The refrigerator pan 24 is further provided with a pair of flanges 25 at each side thereof along the upper marginal edges thereof. It can then be seen that the refrigerator pan 24 is slidably mountable within the inner liner 22, with the flanges 25 of the refrigerator pan 24 within the lower channels of the sides 11 and 13, and with the glass 20 positioned as a cover over the pan 24. The refrigerator pan 24 may further be provided with a flange similar to the flanges 25, mounted along the rear edge of the refrigerator pan 24 so that when the refrigerator pan 24 is projected within the frame 6 beneath the glass 20, the rear flange of the refrigerator pan 24 will engage the lower channel of the side or rear portion 12.

Having described the invention what is considered new and desired to be protected by Letters Patent is:

In a refrigerator drawer assembly, the combination of a refrigerator cabinet having an inner liner provided with side walls and bottom wall, a drawer supporting frame of rectangular shape having one side mounted on said liner and the opposite side supported by a vertical leg secured to said frame and resting on the bottom wall of said liner, the said frame comprising four similar molded frame members, each of said frame members comprising a 10 molded member having a vertical yoke provided with a pair of inwardly extending, integral, parallel flanges, the said flanges being mitered from said yoke to the inner edge of said flanges, and the said yokes each including a bendable metal strip having two end portions imbedded in 15 said yoke and having a central portion exposed between the ends of each pair of adjacent frame members, to permit bending of said exposed portion, the said frame members being arranged in a series with the metal strips between the adjacent ends of the frame members, the metal 20 strips being bent until their imbedded portions extend at right angles to each other in each case, and the mitered edges of the parallel flanges being located adjacent the mitered edges of the adjacent frame member in each case to form a rectangular frame, two of the sides of said 25 frame being also provided with a third inwardly projecting flange, mitered at its ends and located below the first-

mentioned flanges, a sheet of transparent material located between the uppermost flanges of said frame and a drawer having an outwardly projecting guide flange mounted for sliding movement on the lower pair of flanges which are located on the two opposite frame members to provide guides for said drawer, the said transparent sheet forming a cover for said drawer and the free ends of the series of frame members being secured together.
